AUTOMATIC CONTROL FOR THE LET-OFF MECHANISM OF LOOMS

Original Filed March 2, 1943

Fig. 1.

Fig. 2.

A technical drawing showing a vertical assembly. At the top is a rectangular part labeled '19'. Below it is a cylindrical part labeled '22'. A horizontal slot is visible in part 22. A vertical rib or pin labeled '25' extends downwards from part 22. At the very bottom is a rectangular part labeled '23'.

AUTOMATIC CONTROL FOR THE LETOFF
MECHANISM OF LOOMS

Yervant H. Kurkjian, Clifton, N. J.

Original application March 2, 1943, Serial No.
477,743. Divided and this application September 28, 1943, Serial No. 504,182

3 Claims. (Cl. 139—107)

This invention relates to an automatic control for the let-off mechanism of looms, and the like, and has for one of its objects the production of a simple and efficient means for automatically shifting the position of a weight upon the tension control lever to maintain a substantially uniform tension upon the warp which is carried by the beam of a loom.

A further object of this invention is the production of a simple and efficient leverage arrangement and weight-shifting means for use in conjunction with the beam of a loom and the warp carried thereby for maintaining a substantially uniform tension upon the warp.

The present application constitutes a division of my previous application relating to Automatic let-off control, filed March 2, 1943, Serial Number 477,743.

Other objects and advantages of the present invention will appear throughout the following specification and claims.

In the drawing—

Figure 1 is a side elevational view of the structure embodying the present invention;

Figure 2 is a vertical sectional view taken on line 2—2 of Figure 1;

Figure 3 is a sectional view taken on line 3—3 of Figure 1.

By referring to the drawing, it will be seen that 10 designates the usual frame which supports a beam 11 of a suitable type. The beam supports the warp 12 and also carries a brake band 13, the speed of rotation of which is controlled by a brake band 14. The band 14 is anchored at one end to the frame 10, as at 15, and is secured at its opposite end, as at 16, to the brake lever 17, which lever 17 is pivoted, as at 18, to the frame 10.

A control arm 19 is pivoted, as at 20, to the outer end of the brake lever 17 as shown in Figure 1, and this arm 19 carries a warp-contacting roller 21 at its upper end for contacting with the warp which is wound on the beam 11. The lower end of the control arm 19 carries a roller 22 which contacts with the upper face of the outer end of the weight lever 23, and this weight lever 23 is pivotally connected, as at 24, to the frame 10. A drum 25 is also carried near the lower end of the lever 19, and a flexible cable 26 passes over this drum 25. The cable 26 is anchored at one end, as at 27 to the frame 10, and is connected at its opposite end to the slidable weight carriage 28. The carriage 28 is slidably mounted upon the lever 23 and carries a pair of rollers 29 which travel upon the upper face of the lever 23 to facilitate movement.

As the warp is unwound from the beam 11, the roller 21 will be forced against the warp by the weight and leverage associated therewith and the

lever 19 will swing inwardly toward the beam 11 in proportion to the amount of warp unwound therefrom. This movement will cause the roller 22 at the lower end of the lever 19 to move outwardly toward the adjacent end of the weight lever 23. This movement will cause the cable 26 to pull the sliding carriage 28 inwardly and consequently reduce the tension pull on the brake lever 17 and band 14, in ratio to the amount of warp which has been unwound from the beam 11.

Having described the invention, what I claim as new is:

1. An automatic let-off control of the class described comprising a let-off mechanism, a beam forming part of said mechanism, a warp wound upon the beam, a brake drum carried by the beam, a brake band passing over the drum, a brake lever mounted adjacent the drum, the brake band engaging one end of the brake lever, a pivot supporting the brake lever, a warp-engaging arm pivoted to one end of said brake lever, a weight lever, a weight carriage slidable on the weight lever, one end of the warp-engaging arm engaging one end of said weight lever, and a flexible connection between the warp-engaging arm and the weight carriage for drawing the weight carriage inwardly of said weight lever as the warp-engaging arm is swung.

2. An automatic let-off control of the class described comprising a let-off mechanism, a beam forming part of said mechanism, a warp wound upon the beam, a brake drum carried by the beam, a brake band passing over the drum, a brake lever mounted adjacent the drum, the brake band engaging one end of the brake lever, a pivot supporting the brake lever, a warp-engaging arm pivoted to one end of said brake lever, a tension lever, and means controlled by the warp-engaging arm for regulating the tension pull of the tension lever upon the brake lever and brake band to maintain a substantially uniform tension upon the warp in ratio to the amount of warp unwound from the beam.

3. An automatic let-off control of the class described comprising a let-off mechanism, a beam forming part of said mechanism, a warp wound upon the beam, a brake drum carried by the beam, a brake band passing over the drum, a brake lever mounted adjacent the drum, the brake band engaging one end of the brake lever, a pivot supporting the brake lever, a warp-engaging arm pivoted to one end of said brake lever, a weight carried by the weight lever, and means controlled by the warp-engaging lever for shifting said weight upon the weight lever to provide a tension-regulating means.

YERVANT H. KURKJIAN.
